UNITED STATES PATENT OFFICE.

LEO EHRLICH, OF ST. LOUIS, MISSOURI, ASSIGNOR TO AMERICAN REGISTER COMPANY, OF ST. LOUIS, MISSOURI, A CORPORATION OF MISSOURI.

FARE-REGISTER.

No. 922,868.

Specification of Letters Patent. Patented May 25, 1909.

Application filed December 23, 1895. Serial No. 573,125.

To all whom it may concern:

Be it known that I, LEO EHRLICH, a citizen of the United States, residing at St. Louis, in the State of Missouri, have invented a certain new and useful Improvement in Fare-Registers, of which the following is a description, reference being had to the accompanying drawings, forming part of this specification.

10 My invention relates more particularly to improvements upon the machine patented to me by Letters Patent of the United States No. 523,930, dated July 31, 1894, but its several features are applicable to other forms 15 of fare registers as will be understood from the description hereinafter given.

In the accompanying drawings Figure 1 is a face view of the register; Fig. 2 a corresponding view with the dial plate removed; 20 Fig. 2^a a sectional detail of the gong; Fig. 3 a corresponding view with the trip register wheel and pointer, and the pawl-carrier and pawl for actuating it, and some other parts, removed, the pawl-carrier being shown in 25 dotted lines; Fig. 4 a vertical section approximately on the line 4—4 of Fig. 2; Fig. 4^a a perspective detail of the locking arm or lugs on the pawl-carrier; Fig. 5 a sectional detail approximately on the line 5—5 of Fig. 3; 30 Figs. 6, 6^a and 7 detail views of modifications of the controlling or governing devices; Fig. 7^a a sectional detail taken from Fig. 4 but showing a modified arrangement of the parts; Fig. 8 a perspective view of the fastening 35 plate by which the register is secured to the wall of the car; Figs. 9 and 10 sectional details of the fastening-devices; Fig. 11 a perspective view of the locking screw and the key or wrench for turning the same; and Fig. 40 12 a view illustrating means for operating the register when in position in a car.

The same letters of reference are used to represent identical parts in all the figures.

In its general form my new or improved 45 register is substantially the same as the one heretofore patented to me, so that the following description will be directed more particularly to its novel features, such brief references as may be necessary being made 50 to the old construction.

The pointer A which co-operates with the numbered dial B is fastened to the hub of the trip register wheel C mounted upon a post at the center of the machine, as usual. 55 This wheel is actuated by a pawl D carried

by a lever or pawl-carrier E pivoted upon a post at F and yieldingly held in normal position, with the pawl D disengaged from the teeth of the wheel C, by a coiled spring G surrounding a rod H passing through the 60 lower end of the lever E, and confined thereon between said lever and the collar at the upper end of the rod. The pawl-carrier and pawl are actuated by an operating lever I whose inner end is fast to a rock shaft J 65 which also has fast upon it an arm K whose lower end contacts with the pawl carrier E at a and whose upper end contacts with it at b, the lever E being suitably shaped for that purpose. The result is that when the upper 70 end of the lever I is pulled downward the lower end of the arm K will force the pawl-carrier E toward the right and cause the pawl to advance the wheel C the space of one tooth, and thereby cause the pointer to add 75 one number upon the dial, while an upward movement of the outer end of the lever I will cause the upper end of the arm K to force the pawl-carrier E to the right with like result.

80 My new machine, as my former one, is intended to indicate and register different classes of fare, and the means employed for that purpose may be now described. The two registers L and M are mounted in a 85 framework N secured to the back plate of the machine. The wheels of the register L are loose upon a shaft O, Fig. 5, which carries at its inner or left end, Fig. 3, a beveled pinion P which meshes constantly with a 90 beveled gear upon the under side of a trip register wheel C, the shaft O thereby turning with said wheel. Splined upon the outer end of the shaft O is a clutch member Q adapted to be slid backward and forward 95 upon the shaft into and out of engagement with the primary wheel of the register L. In the present instance the clutch engagement is effected by means of one or more pins c projecting from the side of the register-wheel and adapted to co-operate with a toothed disk or gear wheel d fast upon the left hand end of the clutch member Q, Figs. 2, 3 and 5. When the clutch member is shifted to its left hand position the pin fits 100 in the space between two of the teeth of the wheel d, causing the clutch member to carry the wheel with it when the shaft is turned, and when the clutch member is shifted to the right the pin and wheel d are 105 110

- disengaged. When the clutch member is shifted to the right the wheel *d* is thrown into gear with a wheel *e* which meshes with a third wheel *f* fast upon the shaft which supports the register *M*. The primary wheel of this register is fast upon said shaft and hence turns with the wheel *F* and clutch member *Q* and shaft *O*. The clutch member is shifted back and forth, into co-operation with the register *L* and the register *M*, by means of a forked arm *R* engaging a circumferential groove in the clutch member and fast at its opposite end upon the right hand end of a sliding rod *S* mounted in bearings upon the back plate of the machine and carrying at its extreme left hand a roller *T* which fits against the edge of a sector plate *U* fast upon the rock shaft *J* which carries the operating handle *I*, such engagement being enforced by means of a coiled spring *V* surrounding the rod *S* near its right hand end and confined between a pin *W* passed through the said rod and the right hand bearing *X* in which the rod is supported, Fig. 3.
- The upper half of the edge of the sector plate *U* is cut away to form a shoulder or cam on the edge of the plate at *g*, with the result that whenever the outer end of the operating lever *I* is pulled downward and the sector plate *U* thereby thrown upward the rod *S* will be forced to the right and the clutch member be disengaged from the register *L* and thrown into gear with the register *M*, so that the further movement of the parts, by which the trip register wheel is turned, will cause the primary wheel of the register *M* to be advanced. On the contrary, when the operating lever *I* is pulled upward from normal position and the sector plate *U* thereby thrown downward the roller *T* will simply travel upon the edge of the plate above the cam *g* and the rod *S* remain stationary with the clutch member in engagement with the register *L*, so that the latter register will be the one actuated. It will be understood that owing to the position of the pawl *D* the shifting of the clutch member (when it is to be shifted) will be effected before the pawl begins to turn the trip register wheel *C*.
- The pawl carrier *E* has secured to and formed integral with it an arm *a'*, Figs. 2, 4 and 4^a, against whose upper end the pawl is pressed and yieldingly held by a coiled spring *b'*. The upper end of the arm *a'* is shaped to engage the wheel at the limit of movement of the pawl carrier and pawl, and thereby lock the wheel *C* and prevent any overthrow of it by momentum in the case of any quick or violent operation of the machine. The lower end of the arm *a'* serves a purpose hereafter described.
- The transfers between the several wheels of the registers *L* and *M* are effected by the usual transfer pinions *c'*, Fig. 5, while the primary wheels are yieldingly held in position and backward movement of them prevented by the usual spring-pressed holding pawls, Fig. 5.
- The fare indicator, by which the different classes of fares are indicated, consists of a curved plate *Y* supported upon the right hand end of a rock shaft *Z* mounted at its opposite ends in bearings upon the back plate of the machine, Fig. 3, and bears in this instance the words "Ticket" and "Cash", representing those two classes of fare. The extreme left hand end of the shaft *Z* is bent downward or formed with a depending extension *b*², Figs. 3 and 4, standing between and in the path of two lugs *A*' *B*' upon the upper side of the sector plate *U*. When the operating handle *I* is pulled upward the lug *A*' will contact with the downwardly bent end of the shaft *Z* and rock it and carry the indicator to the position shown in Figs. 1, 2 and 5, in which position it will remain, being held by the friction of its bearings or otherwise, until the lever *I* is given a downward operating movement, whereupon the lug *B*' will contact with the end of the shaft *Z* and rock it and shift the indicator *Y* to position to expose the word "Ticket".
- In the manner and by the means above described when the operating handle *I* is given a downward movement the fare indicator will be shifted to expose the word "Ticket", and the register *M* will be actuated to register a ticket fare, and when said handle is given an upward movement the indicator *Y* will be caused to expose the word "Cash", and the register *L* be actuated to register a cash fare.
- The means for resetting the trip register to zero will be next described. The resetting shaft *C'* is mounted to rotate and to slide in and out in bearings *D'* *E'*, as usual, and has fast upon it near its inner end a beveled gear *F'* adapted when the shaft is slid inward to its limit of movement to mesh with the beveled gear upon the under side of the trip register wheel *C*, so that upon then turning the shaft *C'* the trip register wheel may be turned to initial position. Mounted to slide in and out with the shaft *C'* is a frame *G'*, the shaft passing through and being free to turn in openings in the right hand end of the two transverse bars of such frame, said bars fitting against the front and rear ends of the hub of the gear *F'*, so that the frame is carried in and out with the shaft, while the latter turns independently of it. Pivoted to this frame is a latch *H'* which co-operates with a block or plate *I'* fast upon the upper side of the bearing *E'*, to latch the shaft *C'* in its inner position during the resetting operation of the registering wheel. When said wheel reaches initial position a trip *E*², Fig. 4, carried by it disengages the latch from the block *I'* and permits the shaft *C'* to be moved outward to normal position, as usual.

In such outer position the shaft is locked from turning by means of a pawl J' which engages the gear F' at one end and is held in locking engagement therewith by a lug K' 5 projecting upward from the back plate of the machine, upon which lug the rear end of the pawl normally rests. When the shaft is pushed inward the pawl is carried away from this lug, so that its opposite end may yield 10 and permit the gear F' to turn.

It will be noticed that the latch H' has two shoulders or catches, the purpose of which is as follows: The trip indicator G^5 is actuated at each reciprocation of the resetting shaft C' by means of a pawl G^7 carried by the frame G' and engaging a ratchet on the end of the indicator G^5 , Fig. 4. Now, to prevent the shaft C' being pushed in toward resetting position, but not far enough 15 for it to become latched in resetting position, and then moved outward again, and in this manner causing the pawl G^7 to turn the trip indicator, without the trip register having been reset, the double shoulders upon the 20 latch are provided, the inner or upper one of which catches over the block I' as soon as the shaft C' has been slightly pressed in, so that after the shaft has been thus displaced from normal position it cannot be returned thereto 25 without first pressing it in to complete resetting position and turning it until the trip register is reset. Thus the trip indicator can be shifted only at each resetting of the trip register.

30 Instead of shifting the trip indicator G^5 automatically, or incidentally to the resetting of the trip register, it may, if desired be shifted by a positive independent operation. Thus, in Fig. 3 I have shown (in dotted lines) 35 the spindle of the indicator G^5 extended to the right through the casing of the machine and provided with a thumb-piece G^9 by which it may be turned. To normally lock the indicator and prevent its being turned 40 except when the shaft C' is slid in to resetting position, the arm G^9 which acts as a pawl, to turn the indicator under the construction heretofore described, may be shaped to act as a locking arm and coöperate with the 45 squared end of the roller G^6 , as shown in 50 Fig. 7^a. Under such an arrangement the arm G^9 will normally lock the roller from turning, but unlock it when the shaft C' is slid inward to resetting position.

55 During the resetting of the trip register wheel it is necessary that the actuating pawl and the permanent register or registers shall be disengaged from it, and it has been common in machines of this character to provide 60 means for automatically effecting such disengagement when the resetting shaft is pressed inward to resetting position. In my present machine, inasmuch as the actuating pawl D is normally out of engagement with 65 the trip register wheel C it is not necessary to

disengage it from said wheel upon moving the shaft C' to resetting position; but inasmuch as the trip register wheel, under the adjustment illustrated and described, is normally in gear with the permanent register L 70 it follows that they must be disengaged in order to permit the trip register wheel to be reset. This engagement is effected by means of a bell crank L' , Fig. 3, whose upper end fits in a notch in the shifter rod S , and whose 75 lower arm projects in the path of an arm or plate M' secured to the right hand end of the frame G' which moves in and out with the resetting shaft C' , Fig. 4. When said shaft is pressed inward to resetting position the 80 rod S will be shifted so far to the right as to carry the clutch member Q out of engagement with both the register L and the gear e , so that while the shaft is held in such inward position both registers will be disengaged 85 from the trip register. Inasmuch as the rod S is shifted to the right in this operation against the tension of the spring U , as heretofore described, it follows that such spring will operate as a resetting spring for the 90 shaft C' as well, though the latter may be provided with a special spring if desired.

95 For the purpose of locking the operating handle I during the resetting operation of the trip register there is provided a locking dog O' pivoted upon the same pivot F as the pawl-carrier E , and adapted to coöperate at its upper end with a notch P' in the edge of the sector plate N . A pin Q' upon a plate projecting upward from the frame G' fits in 100 a notch in the dog O' and operates when the resetting shaft is pressed inward to force the dog into the notch P' in the plate N and thereby hold such plate and the operating handle I locked from movement so long as 105 the shaft C' remains in resetting position.

The machine is provided with a gong R' sounded by a striker S' , which striker is actuated by a pawl T' pivoted to the pawl-carrier E . The pawl T' is formed with a 110 hook or shoulder upon the under side of its right hand end, which hook is adapted to catch over a tooth or projection U' upon the striker S' when the upper end of the pawl is thrown to the right, and when it moves to the left to normal position the pawl T' pulls the striker to the left against the tension of a spring V' until the hook of the pawl T' slips off the projection U' and releases the striker and permits the spring to throw it 115 against the gong. The pawl T' also serves another purpose, as follows. Its under side rests upon and in its movement to the right rides over a fixed piece W' , in this instance an arm secured to the upper end of a post 120 upon the back plate of the machine. The pawl T' is provided upon its under side with a notch or shoulder h . When the pawl carrier and pawl have been moved a short distance toward the right the shoulder h will 125

catch over the end of the arm W' and prevent return movement of the parts, so that it is then necessary to give the handle a complete stroke and thereby make a full operation of the machine. In the return movement of the parts the shoulder is lifted over the end of the arm W' as the pawl pulls the striker S' backward, and when it becomes disengaged from the striker it drops back to the position shown. The pawl T' in connection with the fixed member W' and striker S' thus serves as a complete stroke device to compel a complete operation of the machine whenever the handle is moved in either direction. The pawl T' serves another purpose in connection with the member W' . The pawl is provided upon its upper edge with a shoulder i arranged to coöperate with the lower end of a rod X' confined in a housing Y' upon the back plate of the machine and pressed downward by a spring. The lower end of this rod X' acts as a stop or abutment to coöperate with the shoulder i on the pawl T' . Under the construction illustrated it will be seen that as such pawl moves forward the stop X' will stand in the path of the shoulder i before the shoulder h clears the end of the arm W' and permits the right hand end of the pawl to drop slightly. Just before the shoulder h clears the end of the arm W' the stop stands squarely in the path of the shoulder i so that if the pawl is being moved quickly to the right the shoulder will strike the stop and arrest the parts before the right hand end of the pawl has time to drop and permit the shoulder to clear the stop. In the ordinary operation of the machine the shoulder h will clear the arm W' and the end of the pawl will drop and permit the shoulder i to clear the stop, so that said shoulder and stop will perform no function, but if it be attempted to operate the machine quickly or violently the shoulder i will contact with the stop and arrest the movement of the operating handle and parts. At the return movement of the parts the right hand end of the pawl will be lifted, as it pulls the striker back, and the stop X' be forced upward into its housing until the hooked end of the pawl slips off the projection on the striker, whereupon the pawl drops back upon the arm W' and the parts resume the position shown. The pawl, in connection with the other devices, thus serves not only as a complete-stroke device, but also as a governor to prevent any violent operation of the machine, and in these respects its operation is entirely distinct from its operation as an actuating device for the gong striker, as will be readily understood. The gong might be removed and the upper end of the gong striker cut off without affecting the operation of the pawl for these purposes, or other means than the gong striker

might be substituted for the latter for the purpose of lifting the end of the pawl in the return movement of the parts to enable the shoulder h to clear the end of the arm or member W' . Again, for the purpose of acting as a governing device it is not necessary that the reciprocating member should be a pawl at all. It may be any reciprocating member, even a special one having no function except as a part of the governing device, and where it is not intended to also serve the purpose of a complete stroke device the shoulder h may be rounded off or inclined, so that in the backward movement of the parts it will ride over the member W' and thus make it unnecessary to lift the end of the reciprocating member to permit the shoulder to clear the part W' . In such case, also, it will not be necessary that the stop X' shall be a yielding one, but on the contrary it may be fixed. Thus in Figs. 6, 6^a and 7 are illustrated three simple constructions and arrangements by which the reciprocating member may be made to operate as a governing device to prevent too quick forward movement of the parts.

As seen in Fig. 6 the stop X' stands in the path of the shoulder i of the reciprocating member A^3 when the latter is in normal position, while the shoulder h on the under side of said member is rounded and the forward end of the member A^3 rests upon the fixed stud or pin B^3 . Under this construction if the parts be moved forward slowly the shoulder h will drop over the pin B^3 before the shoulder i reaches the stop X' , and permit the shoulder i to clear the stop. When, however, the parts are thrown quickly forward the shoulder i will strike the stop. In the backward movement of the parts the shoulder h will ride up over the pin B^3 just after the shoulder i has passed to the left of the stop X' , and the member A^3 thus resumes its normal position.

In Fig. 6^a the stop X' is located to the right of the member A^3 , so that the end of the member A^3 may strike the stop when the member is moved forward too quickly, and thus it is not necessary that the member have any shoulder or projection i .

In Fig. 7 the member A^3 has a shoulder i as in Fig. 6. The stop X' is out of the path of the shoulder i when the member A^3 is in normal position, and the under side of said member in front of the shoulder h is inclined so that as it rides over the pin B^3 the forward end of the member A^3 will be lifted until the shoulder i is carried into the plane of the lower end of the stop. The shoulder h will clear the pin B^3 , however, before the shoulder i strikes the stop X' , and will thus permit the forward end of the member A^3 to drop and the shoulder i to clear the stop X' . When, however, the parts are violently operated

and the member A³ thrown quickly forward the shoulder *i* will strike the stop and arrest the parts.

This feature of my invention is applicable 5 in its broader scope to any device employing a reciprocating member and in which it is desired to prevent violent or exceedingly rapid movement of the parts, and contemplates, broadly, the employment of a stop in combination with a reciprocating member and means for causing the member to strike the stop when moved quickly or violently and to permit it to clear the stop when moved slowly. The yielding stop X¹ of Figs. 2 and 15 3 also performs a useful function in connection with the pawl T¹, quite independently of the fixed member W¹ and the shoulder *h* upon the under side of the pawl. Thus, as the pawl returns toward the left, retracting 20 the striker with it, it will, as its right hand end rises, press the stop X¹ upward into its housing Y¹, and as soon as the shoulder *i* passes to the left of the stop the latter will spring downward in front of it. This occurs 25 before the pawl releases the striker, which release does not take place until the parts have returned almost to normal position. The result is that after the parts have been moved backward far enough for the shoulder *i* to pass 30 the stop X¹ they cannot be moved forward again without first returning them to substantially initial position. This coöperation of the stop X¹ with the shoulder *i* thus insures the complete return stroke of the parts, as the 35 coöperation of the shoulder *h* with the member W¹ insures their complete forward stroke.

The next feature of my invention relates to means for automatically muffling the sound of the gong at the registration of one class of 40 fare, so that the gong will be caused to give forth different sounds at the registrations of different classes of fare, and thereby serve as a means, in addition to or in place of the fare indicator, for distinguishing the two classes 45 of fares. The device employed for this purpose consists in the present instance of an arm fast upon the rock shaft Z which carries the fare indicator Y, and which arm, when the shaft Z is rocked to position to expose 50 the "ticket" sign to view, is thrown against the gong, and serves to deaden or muffle the sound thereof when the gong is struck by the hammer S¹. Under the particular arrangement shown in the drawings the arm fast 55 upon the rock-shaft Z consists of a downward extension c' of the left hand supporting arm of the indicator plate Y, Fig. 2^a, though it may just as well be a separate arm fast upon the shaft, or any other suitably supported arm arranged to be thrown against the gong at the registration of one class of fare, and away from the gong at the registration 60 of the other class of fare. As heretofore stated the fare indicator Y is yieldingly held in its opposite indicating positions

either by the friction of the shaft Z in its bearings or by means of a suitably applied spring, so that when the indicator is thrown into position to indicate a ticket fare the arm c' is pressed against the gong and remains in contact therewith until moved from it by the registration of a cash fare. To add to the muffling effect the lower end of the arm c' which contacts with the gong, may be provided with some sort of a pad if desired.

As above stated, the gong and muffling device may be employed as a substitute for the fare indicator, for indicating the different classes of fares. So far as I am aware I am the first in the art to employ, in a fare register, the combination of a trip register, two permanent registers for registering different classes of fares, and a gong mechanism or alarm mechanism of any kind, (whether a single gong with a muffling device, as described, or two separate gongs), for the purpose described, and my invention in this respect is of corresponding scope.

The next feature of my invention relates to means for increasing the capacity of the trip register to enable it to register more than the number of fares indicated upon the dial, in this instance, as usual, the highest number that may be registered upon the dial being 99. To this end I provide the dial with an opening Y', Fig. 1, at the point where the cipher would otherwise be placed upon the dial, and I place the cipher or zero sign upon an indicator plate located beneath the dial in position to normally expose the cipher at said opening. As seen in Fig. 2 this indicator plate Z' has a widened upper end bearing the cipher and also above it the number 100, while the lower end of the plate extends downward past the center of the machine and is provided with a slot embracing the upper end of the hub of the trip register wheel C, the plate at the opposite sides of the slot fitting in a groove in said hub, Fig. 4. Upon the under side of the plate Z' near its upper end is a plate A² projecting rearward at right angles from the main plate and having an eye through which passes a rod B², Figs. 3 and 4. A coiled spring surrounding said rod and confined between the post which supports the upper end of the rod and the eye plate A² presses the indicator plate downward and tends to carry the number 100 into view at the opening Y' in the dial. The indicator plate is normally held from such downward movement by a latch arm C², Fig. 2, engaging a shoulder formed on the left hand edge of the plate near the center of the machine. This latch arm is provided upon its under side with a lug D² which stands in the path of a trip lug E² fast upon the upper side of the register wheel C. This trip E² is in such position upon the wheel C that just as the latter completes a revolution and brings the pointer around to initial position

it will contact with the lug D² and disengage the latch C² from the indicator plate and permit the spring to throw the plate downward and bring the number 100 into view at the opening Y'. The pointer will then stand at initial position, with 100 exposed to view beneath it, so that it may move on around at succeeding operations of the machine until it has completed any part of a second revolution up to the number 99. In this manner the capacity of the trip register is increased from 99 to 199. It will be evident that its capacity might be still further increased by employing an indicator plate having the number 200 above the number 100, and arranging any suitable means to disengage the latch plate C² at the first revolution of the trip register wheel, and permit the indicator plate to move downward and engage a second shoulder with the latch plate, and then disengage the latch from such second shoulder at the next revolution of the trip register wheel.

For the purpose of restoring the indicator plate to normal position at each resetting of the trip register the following devices are employed: The extreme lower end of the plate Z' is immediately above a pin F² upon the left hand end of an arm G², Fig. 2, which is pivoted at its right hand end to a post upon the back plate, at H². Projecting from the frame G', (Fig. 4,) is a pin I² whose outer end extends into the plane of the arm G² a short distance below the same. When the latch C² is disengaged from the plate Z' and the latter drops to expose the number 100 to view, as before explained, the contact of the lower end of the plate with the pin F² upon the arm G² will carry the latter downward with it (assuming the arm G² to normally rest in its upper position as shown) until they are arrested by the contact of the arm G² with the pin I². They will then remain in this lower position until the resetting shaft C' is slid inward (or upward) to resetting position, whereupon, inasmuch as the frame G' moves with said shaft as heretofore described, the pin I² carried by said frame will lift the arm G² and indicator plate Z' to normal position and cause the latch C² to reengage the shoulder on the plate and support the latter in normal position, with its cipher exposed to view, ready for the next round of operations.

So far as I am aware I am the first in the art to combine an auxiliary indicator with the dial of the trip register, to increase the capacity of the latter in this manner, regardless of the form and arrangement of said indicator or the particular means for operating it. My invention is therefore of corresponding scope and limited only by the terms of my respective claims in which it is set forth. Thus, inasmuch as it is a common alternative in indicating devices

to expose the indicator either by moving the indicator itself from behind a screen or by moving a screen from before the indicator, it will be evident that instead of placing the number 100 upon a movable plate and moving it into view at the opening in the dial, it might be placed upon a fixed plate immediately beneath said opening and a movable plate such as Z' be employed simply as a screen plate to hide and expose the number. In such event the cipher might be placed upon such movable plate and be normally exposed to view at the opening in the dial and be withdrawn from view when the plate was moved to expose the number, as will be readily understood. Again, even when the indicating number is placed upon a movable plate operating as described it is not essential that the cipher should be placed upon such plate. It might be placed on a fixed plate immediately beneath the opening in the dial and the plate Z' be so shaped or cut away as to expose the cipher when the plate was in normal position, but to hide it when moved to expose its number 100 to view; or the cipher may be omitted entirely, or be placed upon the dial. Again, in event the auxiliary indicator were provided with two indicating numbers, as heretofore suggested, the dial and pointer might be arranged to register a hundred fares at less than a complete revolution of the pointer—as a half revolution, for instance—in which event the auxiliary indicator would be arranged to be moved at the end of such portion of a revolution of the pointer, instead of at the end of its complete revolution as described. It will also be understood that the auxiliary indicator might be positively moved into indicating position, instead of being moved by a spring and normally held from movement by a latch.

For the purpose of preventing backward movement of the operating handle I after it has been moved in either direction from normal position the lower end of the vertically extending arm a' of the pawl-carrier (heretofore described) is arranged to coöperate with the lug B' of the sector plate U in the following manner: The normal position of the lower end of the arm a' in relation to the lug B' is indicated in dotted lines in Fig. 3. Now, when the handle I is moved in either direction from normal position the pawl-carrier and arm a' are forced to the right, as heretofore explained. If the handle is pulled downward the lug B' will be moved upward, out of the path of travel of the lower end of the arm a' toward the right, while if the handle is thrown upward the lug B' will be moved downward, likewise out of the path of travel of the arm a'. Now, about the time the pawl-carrier has been moved far enough to the right to carry the arm a' either im-

mediately above or immediately below the lug B', (according to the direction in which the handle I is moved,) the shoulder h of the pawl T' will catch over the fixed member W' and prevent any backward movement of the pawl-carrier, in the manner heretofore explained. This will hold the arm a' directly in the return path of the lug B' and prevent any backward movement of the operating handle until said handle and the parts moved by it are given a complete forward movement, to make a registration and sound the gong, as heretofore described. In this manner the coöperation of the arm a' with the lug B' compels a complete stroke of the operating handle in either direction in which it may be started, and makes it impossible to move the handle in one direction far enough to engage the shoulder of the pawl T' with the member W', and then reverse the movement of the handle and complete the movement of the pawl-carrier by a stroke of the handle in the opposite direction, as might otherwise be done.

The next feature of my invention relates to novel means for attaching registers of this class to the walls of the cars in which they are used. Heretofore the means usually employed for attaching the register to the wall of the car has consisted of a flat lug or short plate projecting radially from the back plate of the register at one side, and a hasp projecting from it at its opposite side, the former being adapted to fit in a metal pocket or receptacle permanently secured to the wall of the car, and the latter being adapted to fit over a staple driven in the wall of the car, the register being then secured in position by a pad-lock applied to the staple. There are several objections to this method of attaching the registers, among which is the difficulty of securing them firmly to the wall of the car, and preventing them being jarred and shaken both by the motions of the car and by the operations of the machines in registering fares. I have provided novel, simple and efficient means for securing the register to the wall of the car with perfect rigidity and firmness but at the same time permitting it to be easily and quickly detached and removed whenever desired. The devices I employ for this purpose are shown more particularly in Figs. 8 to 11. In the former figure J² represents what may be called the attaching plate, consisting in this instance of a circular plate of somewhat less diameter than the register itself, and provided with a number of holes j for the passage of screws by which the plate is permanently secured to the wall of the car. The plate is provided with a series of integral posts K², in this instance three in number. These posts are cut away at their upper or outer ends to form shoulders or seats k and flanged heads l.

The back or base plate L² of the register is provided with a series of holes coincident with the several posts K² and large enough to fit over the heads l of the posts, but not large enough to pass over the bodies of the posts. 70 When the register is placed in position upon the attaching plate, therefore, the back plate of the register rests upon the shoulders or seats k of the posts, Figs. 2, 3, 4, 10 and 11. Now, the spaces between the shoulders k and flanged heads l of the posts are sufficient to accommodate the thickness of the back plate L² of the register, so that when the attaching plate is secured in vertical position upon the wall of the car and the register is then applied 75 to it, the register will slip downward upon the plate to the position indicated by the drawings, the back plate of the register fitting between the shoulders and flanged heads of the posts at the upper sides of the latter, 80 as shown. In such position it is not possible to disengage the register from the attaching plate without first slipping it upward, to disengage its back plate from the flanged heads 85 of the posts. By providing means, therefore, to lock the register in its lower position upon the attaching plate and bind it against the posts it may be secured to the wall of the car with perfect rigidity and firmness. Any suitable means for this purpose may be employed, the novel means devised by me being 90 shown in Figs. 4, 19 and 12. As shown the lower one of the three posts K² and its coincident hole in the plate L² are immediately above the lower or outer bearing D' of the 95 resetting shaft C'. Formed in this bearing or lug D' near its base is a threaded hole in which is screwed a locking or binding screw M². The inner or upper end of this screw bears against the lower side of the head of 100 the adjacent post K², the head of the post being flattened where it fits against the end of the screw. When the screw is screwed in until it presses firmly against the head of the post it will bind the back plate of the register 105 upon all of the posts in the position shown in the drawings and thereby securely and rigidly fasten the register to the attaching plate 110 and thereby to the wall of the car. The locking screw may be turned by any 115 suitable key or wrench, such for instance as that shown in Fig. 12. The inner end of the wrench N² there shown is hollow and adapted to fit over the reduced outer end of the screw M², and is provided upon its opposite sides 120 with two ears or projections m adapted to fit in recesses n cut in the sides of the body of the screw. So far as I am aware I am the first in the 125 art to secure registers of this class to the walls of the cars by means of attaching plates permanently secured to the walls of the cars and provided with posts or projections supporting the registers and coöperating with openings in the back plates thereof in the manner 13.

described, or in any similar manner, and my invention is therefore of corresponding scope.

The remaining feature of my invention relates to novel means for actuating the register from different points along the car, and is shown in Fig. 12. As there shown the operating devices are arranged for the operation of the register from any point along the car, upon either side thereof, and are especially 10 designed for use upon open cars, where the conductor passes along the sides of the car upon the foot-boards as he collects the fares. In closed cars, where the conductor passes along the middle aisle, it is not necessary to 15 have both sets of operating devices, as he can readily reach the handles of the one set wherever he may be standing. As shown in Fig. 12 the operating handle or lever I of the register is arranged in vertical position, instead of in longitudinal position as in Figs. 1 20 to 3. Its lower end is connected by a link or bar O² with the upper end of an arm P² fast upon and extending upward from a rock shaft Q² journaled in brackets R² secured to 25 the frame-work S² of the car and extending from front to rear thereof. The shaft Q² has fastened upon it at convenient intervals and within reach of the conductor horizontally projecting operating handles T². Upon 30 grasping any one of these handles and depressing it the lower end of the lever I of the register will be thrown toward the left and a cash fare be registered; while upon lifting any one of such handles the lever I will be 35 thrown to the right and a ticket fare be registered.

As before stated the single set of operating devices just described is sufficient for a closed car, but upon an open car they will preferably be duplicated, as shown in Fig. 12, where it will be seen that the lower end of the lever I is also connected by a link or bar U² to an arm V² secured to and depending from a rock shaft X² at the opposite side of the car 40 and similar to the shaft Q², journaled in brackets Y² and provided with horizontally projecting operating handles Z² corresponding to the handles T². Owing to the fact that the arm P² of the rock shaft Q² extends upwardly from said shaft, while the arm V² of the shaft X² extends downwardly from said shaft, the depression of the handles T² and Z² have the same effect upon the register, to-wit, the registration and indication of a cash 45 fare; while the lifting of either of said handles has the same effect as the lifting of the other, to-wit, the registration and indication of a ticket fare. The conductor may, therefore, by depressing any one of the handles at 50 any point in the car indicate and register a cash fare, while by lifting any one of them he may indicate and register a ticket fare or transfer.

So far as I am aware I am the first in the art to combine, in any manner, a fare register capable of registering different classes of

fares, with a rock-shaft extending along the car and provided with a series of operating handles whose movements in one direction will actuate the register to register one class of fare and whose movements in the opposite direction will actuate it to register the other class of fare. Such being the case this feature of my invention is not restricted either to the particular form of register shown and described or to the particular means for connecting the rock-shaft with the register. Thus, for instance, the invention is equally applicable to registers having two independent operating handles or actuating devices, one for registering one class of fare and the other for registering the other class, in which event the rock-shaft may be connected with both of such handles or operating devices in such manner that its movement in one direction will actuate one of them while its movement in the other direction will actuate the other, for the purpose described. Two rock-shafts extending along opposite sides of the car may likewise be connected with a register having two independent actuating devices in such manner that the movement of either shaft in one direction will register one class of fare and the movement of it in the other direction the other class of fare, as will be readily understood.

Having thus fully described my invention, I claim:

1. In a fare register, the combination, with the trip register wheel, of a shaft permanently in gear therewith, a permanent register, a clutch member for connecting and disconnecting the shaft and permanent register, resetting means for the trip register, and means for shifting the clutch at each resetting of the trip register, to disconnect the permanent register from the trip register and permit the resetting of the latter, substantially as described.

2. In a fare register, the combination, with the trip register wheel, of a shaft permanently in gear therewith, a permanent register, a clutch member for connecting and disconnecting the shaft and permanent register, resetting means for the trip register, and a shifter for the clutch operated by said resetting means to disconnect the permanent register and shaft, substantially as described.

3. In a fare register, the combination, with the trip register wheel, of a shaft permanently in gear therewith, a register wheel loose upon said shaft, a clutch for connecting and disconnecting them, a resetting shaft for the trip register wheel, and a shifter for the clutch operating to disconnect the registering wheel and shaft when the resetting shaft is moved to resetting position, substantially as described.

4. In a fare register, the combination of a trip register wheel, a permanent register, a shaft permanently in gear with the trip regis-

ter wheel, a connecting member splined upon said shaft and adapted to connect the same with and disconnect it from the permanent register, a resetting shaft for the trip register, 5 and a shifter operated by the resetting shaft to move the connecting member to disconnect the trip register and permanent register when the resetting shaft is moved to resetting position, substantially as described.

10 5. In a fare register or other device having a reciprocating member, the combination, with such member provided with a shoulder or projection, a fixed member over which the shoulder of the reciprocating member is 15 adapted to catch in the forward movement of said member, and means coöperating with the reciprocating member after the completion of its forward movement to carry the shoulder of said member out of the plane of 20 the fixed member at the backward movement of the reciprocating member, substantially as and for the purpose described.

6. In a fare register or other device, the combination of a reciprocating member, 25 having the shoulder *h*, the fixed member *W'* adapted to coöperate with said shoulder, and a pivoted member, adapted to be caught by the hooked end of the member *T'* and carried backward part of the way with it and 30 thereby lift the shoulder *h* over the end of the member *W'*, substantially as described.

7. In a fare register, the combination of the hooked pawl *T'* having the shoulder *h*, the fixed arm *W'*, the gong *R'*, and the gong 35 striker *S'* coöperating with the hooked end of the pawl *T'*, in the manner described.

8. In a fare register or other device, the combination of a reciprocating member, a stop or abutment, and means coöperating 40 with the reciprocating member to cause it to contact with the stop when moved quickly or violently, but permitting it to clear the stop when moved slowly, substantially as described.

45 9. In a fare register or other device, the combination of a stop or abutment, a reciprocating member having a shoulder or offset on one side, and a fixed member coöperating with said reciprocating member and its offset or shoulder to cause said reciprocating member to contact with the stop or abutment when moved quickly but permit it to clear the stop when moved slowly, substantially as described.

55 10. In a fare register or other device, the combination of a stop or abutment, a reciprocating member having a shoulder or projection on its side adjacent said stop, and means at the opposite side of the reciprocating member coöperating therewith to cause the shoulder to strike the stop when the member is moved quickly or violently, and to permit it to clear the stop when moved slowly, substantially as described.

65 11. In a fare register or other device, the

combination of a stop or abutment, a reciprocating member having a shoulder or projection on its side adjacent said stop and an off-set or shoulder on its opposite side, and a fixed member adjacent the latter side of the reciprocating member and coöperating therewith and with its shoulder or off-set to cause the shoulder upon the opposite side of the reciprocating member to contact with the stop or abutment when the member is moved quickly and permitting it to clear the stop when the member is moved slowly, substantially as described.

70 12. In a fare register or other device, the combination of a stop or abutment, a reciprocating member normally out of the plane thereof, and means coöperating with the reciprocating member to carry it, when quickly or violently moved, into contact with the stop but permitting it to clear the latter when moved slowly, substantially as described.

75 13. In a fare register or other device, the combination of a stop or abutment, a reciprocating member having a shoulder on its side adjacent said stop and normally out of the plane thereof, and a fixed member at the opposite side of the reciprocating member coöperating therewith to move it, when quickly or violently operated, to position to cause its shoulder to strike the stop, but permitting the shoulder to clear the stop when the member is moved slowly, substantially as described.

80 14. In a fare register or other device, the combination of a stop *X'*, a reciprocating member, *T'*, having a shoulder *i*, and a fixed member, *W'*, over which the member, *T'* rides in its forward movement and coöperating therewith to cause the shoulder *i* to strike the stop *X'* when the member *T'* is moved quickly, and permitting the said shoulder to clear the stop when it is moved slowly, substantially as described.

85 15. In a fare register or other device, the combination of the yielding stop *X'*, a reciprocating member *T'* having the shoulder *i* on its side adjacent the stop *X'* and the shoulder *h* on its opposite side, the fixed member *W'* upon which the member *T'* rests and travels in its forward movement, and means, coöperating with the member *T'* at the end of its forward movement to lift it as it moves backward and carry the shoulder *h* over the end of the member *W'*, substantially as described.

90 16. In a fare register, the combination of the yielding stop *X'*, the pawl *T'* having the shoulders *i* and *h*, the fixed member *W'*, the gong *R'*, and the gong striker *S'* coöperating with the hooked end of the pawl *T'*, substantially as described.

95 17. In a fare register or other device, the combination of a reciprocating member, having a shoulder or projection upon one side, a yielding stop, and means coöperating

with the reciprocating member to lift one end of it at the beginning of its backward stroke and thereby cause it to engage the yielding stop and displace the latter until after the 5 shoulder has cleared the stop, whereupon the stop enters the return forward path of the shoulder and necessitates the return of the reciprocating member to initial position, substantially as described.

10 18. The combination of the reciprocating member T' having the hooked end and provided with the shoulder *i*, of the pivoted member S' having the projection U' coöperating with the hooked end of the member 15 T', and the yielding stop X' coöperating with the member T' and its shoulder *i*, substantially as and for the purpose described.

19. In a fare register, the combination of the reciprocating pawl T' having the shoulder *i* and the hooked end, the gong R', the gong striker S' having the projection U' coöperating with the hooked end of the pawl T', and the yielding stop X' coöperating with the pawl T' and its shoulder *i*, substantially 25 as described.

20. In a fare register, the combination of the arms or plates K U oscillating together and the latter provided with a lug or projection B', the pawl-carrier E actuated by the 30 arm K and having a projection a' coöperating with the lug B' of the plate U, and means for preventing return of the pawl-carrier to initial position, after it has been moved forward therefrom, until it has been given a 35 complete forward movement, for the purpose described.

21. In a fare register, the combination of the rock shaft J and the operating lever I and the arms or plates K U fast thereon, the 40 plate U being provided with a lug or projection B', the pawl-carrier E actuated by the arm K and having a projection a' coöperating with the lug B', the pawl T' having the shoulder *h*, the fixed member W' coöperating 45 with the shoulder *h* of the pawl, and a pivoted member, as S', having the projection U' coöperating with the hooked end of the pawl T', as and for the purpose described.

22. In a fare register employing a fixed 50 circular dial and a rotary pointer movable thereover to indicate the number of fares collected on a single trip, the combination, with such fixed dial and rotary pointer, of an auxiliary indicator located beneath the dial and 55 normally hidden, and means operating to automatically expose it to view at the end of a complete rotation of the pointer over the dial, for the purpose described.

23. In a fare register, the combination, 60 with the pointer and dial of the trip register, the latter provided with an opening opposite the initial position of the pointer, of a movable plate arranged beneath the dial and provided with a cipher normally exposed at the 65 opening in the dial and with a number nor-

mally hidden, and means for moving said plate at the end of a revolution of the pointer into position to hide the cipher and expose the number upon said plate to view at the opening in the dial, for the purpose de- 70 scribed.

24. In a fare register employing a fixed circular dial and a rotary pointer movable thereover to indicate the number of fares collected on a single trip, the combination, with such fixed dial and rotary pointer, of an auxiliary indicator located beneath the dial and normally hidden, and means operated by the rotary movement of the pointer over the dial to automatically expose said indicator to 80 view at the end of a complete rotation of the pointer over said dial, for the purpose described.

25. In a fare register employing a fixed circular dial and a rotary pointer movable 85 thereover to indicate the number of fares collected on a single trip, the combination, with such fixed dial and rotary pointer, of a movable indicator plate located beneath the fixed dial adjacent the initial position of the 90 pointer and provided with a figure normally hidden from view, and means operated by the rotary movement of the pointer over the dial to cause said plate to automatically move into position to expose its figure to 95 view at the end of a complete rotation of the pointer over the dial, for the purpose described.

26. In a fare register, the combination, with the pointer and dial of the trip register, 100 the dial being provided with an opening opposite the initial position of the pointer, of an auxiliary indicator arranged adjacent said opening and having a cipher normally exposed and a number normally hidden, and means coöperating with the trip register for automatically exposing the number and hiding the cipher at the end of a pre-determined movement of the pointer, for the purpose described. 105

27. In a fare register, the combination, with the pointer and dial of the trip register, the latter provided with an opening opposite the initial position of the pointer, of a movable indicator plate arranged beneath the 115 dial and provided with a cipher normally exposed to view at the opening and with a number normally hidden from view, and means coöperating with the trip register to automatically move said plate into position to expose its number to view at said opening, for the purpose described.

28. In a fare register, the combination, with the pointer and dial of the trip register, of an auxiliary indicator coöperating therewith and normally hidden from view, means tending to move it to indicating position, a latch or detent for holding it in non-indicating position, and a trip for the latch operated by the trip register to release the indicator 125 130

and permit it to move to indicating position, for the purpose described.

29. In a fare register, the combination, with the pointer and dial of the trip register, the latter provided with an opening, of a movable indicator plate arranged beneath the dial adjacent the opening and bearing a number normally hidden from view, and tending to move into position to expose its 10 number to view at the opening, a latch or 15 detent coöperating with the plate to hold it in normal position, and a trip for the latch operated by the trip register to release the plate and permit it to move to indicating position, 15 for the purpose described.

30. In a fare register, the combination, with the pointer and dial of the trip register, the latter provided with an opening opposite the initial position of the pointer, of a movable indicator arranged beneath the dial and provided with a cipher normally exposed at the opening and with a number normally hidden, a spring tending to move the indicator to position to expose its number to view at 25 the opening, a latch for holding the indicator in normal position, and a trip for the latch actuated by the trip register to release the indicator at the end of a revolution of the pointer and permit the spring to move it to 30 position to expose its number to view at the opening, for the purpose described.

31. In a fare register employing a fixed circular dial and a rotary pointer movable there over to indicate the number of fares collected on a single trip, the combination, with such fixed dial and rotary pointer, of an auxiliary indicator arranged adjacent the initial position of the pointer and coöperating with the pointer and dial to increase the 35 capacity of the trip register, means for turning the pointer backward over the dial to initial position, and means for returning the auxiliary indicator to normal position at each backward movement of the pointer, for 45 the purpose described.

32. In a fare register employing a fixed circular dial and a rotary pointer movable there over to indicate the number of fares collected on a single trip, the combination, with such fixed dial and rotary pointer, of an auxiliary indicator arranged beneath the dial adjacent the initial position of the pointer and normally hidden from view, means for exposing it to view at the end of a complete 50 rotation of the pointer over the dial, means for turning the pointer backward over the dial to initial position, and means operated by such backward movement of the pointer for restoring the auxiliary indicator to normal 55 position, for the purpose described.

33. In a fare register, the combination, with the pointer and dial of the trip register, the latter provided with an opening, of a movable indicator plate arranged beneath 60 the dial and provided with a cipher nor-

mally exposed to view at the opening and with a number normally hidden, means coöperating with the trip register for automatically moving said plate into position to expose its number and hide the cipher at the 70 end of a predetermined movement of the pointer, resetting means for the trip register, and means coöperating with such resetting means to restore the indicator plate to normal position at each resetting of the trip 75 register.

34. In a fare register employing a fixed circular dial and a rotary pointer movable there over to indicate the number of fares collected on a single trip, the combination, 80 with such fixed dial and rotary pointer, of an auxiliary indicator normally hidden from view and independent of the dial as to its numbers, means coöperating with the rotary pointer for automatically exposing the indicator to view at the end of a complete rotation of the pointer over the dial, means for moving the pointer backward over the dial to initial position, and means operated by such backward movement of the pointer for 85 restoring the auxiliary indicator to normal 90 position.

35. In a fare register, the combination, with the pointer and dial of the trip register, of an auxiliary indicator coöperating therewith, means tending to expose it to view, a latch or detent for holding it unexposed, a trip for the latch operated by the trip register, for the purpose described, resetting means for the register, and means coöperating 95 with such resetting means to restore the indicator to normal position at each resetting of the trip register.

36. In a fare register, the combination, with the pointer and dial of the trip register, 105 the latter provided with an opening, of a movable indicator plate arranged beneath the dial and provided with a number normally hidden from view, a spring tending to move said plate into position to expose its 110 number to view at the opening in the dial, a latch for holding the plate in normal position, a trip for the latch operated by the trip register, resetting means for the trip register, and means actuated by such resetting means 115 to restore the indicator plate to normal position at each resetting of the trip register.

37. In a fare register, the combination, with the pointer A and dial B, the latter provided with the opening Y', of the indicator plate Z' arranged beneath the dial and provided with the number 100 adjacent the opening Y' but normally hidden from view, a spring tending to move the plate Z' to position to expose said number, the latch C² coöperating with the plate to hold it in normal position against the stress of the spring, and a trip for the latch operated by the trip register, substantially as and for the purpose 120 described.

38. In a fare register, the combination, with the pointer A and dial B, the latter provided with the opening Y', of the indicator plate Z' arranged beneath the dial and provided with the number 100 adjacent the opening Y' but normally hidden from view, a spring tending to move the plate Z' to position to expose said number, the latch C² co-operating with the plate to hold it in normal position against the stress of the spring, a trip for the latch operated by the trip register, the endwise movable resetting shaft C', and means intermediate said shaft and the indicator plate Z' for resetting the latter at each resetting of the trip register, substantially as and for the purpose described.

39. The combination, with a fare register, of an attaching plate adapted to be permanently secured to the wall of the car and provided with a series of integral posts having flanged heads adapted to coöperate with recesses or openings in the back plate of the register in the manner described, and means for securing the register in place upon said posts with the flanges of the latter engaging the back plate of the register and preventing removal thereof.

40. The combination, with a fare register, of an attaching plate adapted to be permanently secured to the wall of the car and provided with a series of integral posts having flanged heads coöperating with holes in the back plate of the register, and means coöperating with one of said posts for binding or clamping the register in position upon all of the posts with the flanged heads of the latter engaging the back plate of the register and preventing its removal.

41. The combination, with a fare register, of the attaching plate J² having the posts K² provided with the flanged heads l and shoulders or seats k, said heads being adapted to pass through holes in the back plate L² of the register and permitting said back plate to rest upon the shoulders k, and a binding or clamping screw M² fitting in a threaded bore in the register frame and engaging one of the posts K², thereby binding or clamping the back plate and all of the posts substantially as described.

42. The combination, with a fare register, of the attaching plate J² having the posts K² provided with the flanged heads l and shoulders or seats k, said heads being adapted to pass through holes in the back plate L² of the register and permit said back plate to rest upon the shoulders k, and the clamping or binding screw M² fitting in a threaded bore in the base of the support D' of the resetting shaft C' and engaging the head l of the post K² beneath said shaft, said screw having the projecting reduced portion and notches n n adapted to coöperate with the key or wrench N², substantially as described.

43. The combination, with a fare register

employing two registers for registering different classes of fares, and means for actuating either register at will to register the corresponding class of fare, of a rock-shaft mounted in suitable supports and extending longitudinally of the car in which the register is used, and adapted to be rocked in opposite directions from normal position connections between said shaft and the operating devices of the register by which the turning of the shaft in one direction from normal position will actuate the register to register one class of fare while the turning of it in the opposite direction from normal position will actuate it to register the other class of fare, and a series of handles projecting from the rock shaft, whereby upon moving any one of said handles in one direction from normal position one class of fare will be registered upon the register, while upon moving any one of them in the opposite direction from normal position the other class of fare will be registered.

44. The combination, with a fare register employing two registers for registering different classes of fares, and means for actuating either register at will to register the corresponding class of fare, of two rock-shafts mounted in suitable supports and extending along opposite sides of the car in which the register is used, and each adapted to be rocked in opposite directions from normal position, a series of handles projecting from said rock-shafts, and connections between said shafts and the actuating devices of the register by which the movement of the handles of either shaft in a given direction from normal position will actuate the register to register one class of fare, while the movement of either set of handles in the opposite direction from normal position will actuate the register to register the other class of fare, whereby the movement of any one of either series of handles in one direction from normal position will cause one class of fare to be registered, while the movement of any one of them in the opposite direction from normal position will cause the other class of fare to be registered.

45. The combination, with a fare register embodying a trip register and two permanent registers for registering different classes of fares and means for actuating at will the trip register and either permanent register, to register the corresponding class of fare, of a rock-shaft mounted in suitable supports and extending longitudinally of the car in which the register is used, and adapted to be rocked in opposite directions from normal position connections between said shaft and the operating devices of the register by which the turning of the shaft in one direction from normal position will actuate the trip register and one permanent register to register one class of fare while the turning of

it in the opposite direction from normal position will actuate the trip register and the other permanent register to register the other class of fare, and a series of handles projecting from the rock-shaft, whereby upon moving any one of said handles in one direction from normal position one class of fare will be registered upon the fare register, while upon moving any one of them in the opposite direction from normal position the other class of fare will be registered.

46. The combination, with a fare register embodying a trip register and two permanent registers for registering different classes of fares, and means for actuating at will the trip register and either permanent register, to register the corresponding class of fare, of two rock-shafts mounted in suitable supports and extending along opposite sides of the car in which the register is used, and each adapted to be rocked in opposite directions from normal position a series of handles projecting from said rock-shafts, and connections between said shafts and the actuating devices of the register by which the movement of the handles of either shaft in a given direction from normal position will actuate the trip register and one of the permanent registers, while the movement of either set of handles in the opposite direction from normal position will actuate the trip register and the other permanent register, whereby the movement of any one of either series of handles in one direction from normal position will cause one class of fare to be registered, while the movement of any one of them in the opposite direction from normal position will cause the other class of fare to be registered.

47. The combination, with a fare register embodying a trip register and two permanent registers for registering different classes of fares, and having the operating lever I whose movement in one direction causes one class of fare to be registered and whose movement in the opposite direction causes the other class of fare to be registered, of the two rock-shafts Q² X² mounted in suitable supports along the sides of the car in which the register is used, and each adapted to be rocked in opposite directions from normal position, the arms P² V² fast upon the respective shafts and one projecting above its

shaft and the other below its shaft, the links or bars O² U² connecting the arms P² V² with the lever I, and a series of handles T² Z² fast upon the respective shafts, substantially as and for the purpose described.

48. In a fare register, the combination, with the trip register and resetting devices therefor embodying an endwise movable resetting shaft, and a trip indicator actuated by the endwise movements of said resetting shaft, of a latch for holding the shaft in resetting position when moved thereto, said latch having two latching engagements, the one for holding the shaft in resetting position and the other for preventing return of it to normal position when moved toward but not completely to resetting position, and a trip for the latch operated by the trip register, whereby shifting of the trip indicator by means of the resetting shaft without resetting the trip register is prevented.

49. In a fare register, the combination, with a trip register and two permanent registers for registering different classes of fares, means for actuating the trip register and either permanent register at will, a fare indicator for indicating the different classes of fares, and a gong and sounding mechanism therefor, of a muffling or deadening device operated by the fare indicator and co-operating with the gong to muffle or deaden the sound of the latter when the indicator is moved to position to indicate one class of fare, and to permit the gong to give forth a clear sound when the indicator is moved to position to indicate the other class of fare.

50. In a fare register, the combination, with a trip register and two permanent registers for registering different classes of fares, means for actuating the trip register and either permanent register at will, and the gong and a sounding mechanism therefor, of the fare indicator for indicating the different classes of fare, the rock shaft Z actuated by the operating means of the register to shift the fare indicator to indicate the different classes of fare, and the arm e' carried by the shaft Z and co-operating with the gong in the manner and for the purpose described.

LEO EHRLICH.
